UNITED STATES PATENT OFFICE.

IRA W. SHALER, OF BROOKLYN, NEW YORK.

IMPROVEMENT IN LAMPS.

Specification forming part of Letters Patent No. 123,940, dated February 20, 1872.

To all whom it may concern:

Be it known that I, IRA W. SHALER, of Brooklyn, Kings county, New York State, have invented certain new and useful Improvements in Lamps and Lamp-Burners, of which the following is a specification:

My invention is directed to obtaining a more perfect consumption of the products of combustion in flat-wick lamps and lamp-burners.

In order to produce the result which I have in view I have found the following elements necessary: First, a deflector, provided with an oblong flame-slot, which has its edges serrated, indented, or is equivalently-formed, in order to deliver a comparatively narrow and long flame, the serrations or indentures in the edges of the slot, or the equivalent formation of that part of the deflector in the immediate neighborhood of the slot serving to supply the flame at the flame-slot with a comparatively large volume of air, and to bring about a very intimate mixture of the flame therewith. Second, a chimney provided with a contracted neck with an oblong opening in it over the slot in the deflector, and serving to direct additional air-currents upon the flame rising from the slotted deflector at the point where it passes up through the oblong contracted chimney-neck.

To enable others skilled in the art to understand and use my invention, I will now proceed to describe the manner in which the same is or may be carried into effect by reference to the accompanying drawing, in which—

Figure 1 is a vertical central section of a complete lamp made in accordance with my invention. Fig. 2 is a perspective view of the burner without the chimney. Fig. 3 is a top view of the chimney.

The burner, with the exception of the deflector, is of any usual construction, provided with wick-raising devices, screw-threaded base, air-distributer, and one or more wick-tubes. The one shown in illustration of my invention is of the "sun-burner" type, *a* being the screw-threaded base; *b*, the perforated air-distributer and chimney-rest; *c*, a single wick-tube; and *d*, the wick-raiser. The deflector *e* is supported in an elevated position above the perforated air-distributer, as usual in this class of burners. The flame-slot is shown at *f*, its edges being serrated or indented, so as to

form a series of small projections or fingers, which serve both to admit an increased supply of air to the flame, and to bring about an admixture of this air with the flame passing through the slot. I prefer to form the slot as shown in the drawing but it may be varied somewhat without departure from the invention. An ordinary sun-burner chimney, or chimney with straight sides, will not answer with this burner, as I have found it impossible, with such chimney, to produce a brilliant flame, or to prevent the lamp from smoking. The chimney which I employ has a base, *g*, to fit the chimney-rest of the burner; a contracted neck, *h*, with an oblong opening in it to correspond with the slot in the deflector, and above the contracted neck a flue, *i*, of the requisite length. The contracted neck, with its oblong opening, is indispensable to produce the proper consumption of the products of combustion, forming as it were a second deflector above the metallic deflector *e*, and this second deflector should also be transparent, as a considerable portion of the illuminating flame is below the contracted neck. The form of the chimney-flue *i* may be varied but I have found the best results by far to be produced by the employment of a flue of the oval or elliptical form shown in the drawing, having at least the same area at the top as at the bottom, where its outward curve above the contracted neck terminates. The air which passes through the contracted neck, and forms a second draught, is supplied in any suitable manner; in this instance it passes up through the spaces between the outer edge of the deflector and the base of the chimney, and is directed by the curved sides of the base to impinge upon the flame at the point where it passes through the contracted neck.

With a lamp such as described, the various oils and fluids now generally in use for illuminating purposes can be employed to great advantage. A more perfect combustion is brought about, and a very brilliant flame is produced. The flame is not so broad as in ordinary burners or lamps, but is somewhat narrower and considerably longer.

Having described my invention and the manner in which the same is or may be carried into effect, what I claim, and desire to secure by Letters Patent, is—

The combination, in flat-wick lamps, or lamp-burners of otherwise ordinary or suitable construction, of a deflector having a serrated or equivalently-formed oblong flame-slot, with a chimney having a contracted neck with an oblong flame-passage, substantially as shown and described.

In testimony whereof I have signed my name to this specification in the presence of two subscribing witnesses.

IRA W. SHALER.
